Arnold Zavell, New York, N. Y.

Application August 5, 1941, Serial No. 102,681

Term of patent 3½ years

To all whom it may concern:

Be it known that I, Arnold Zavell, a citizen of the United States, residing in the city, county, and State of New York, have invented a new, original, and ornamental Design for a Textile Fabric or Similar Article, of which the following is a specification, reference being had to the accompanying drawing, forming a part thereof.

The figure of the drawing is a plan view of a textile fabric or similar article showing my new design.

The area within the dot and dash lines shows one complete unit of the design. The repeats are arranged in vertical rows and adjacent vertical rows are one-half a complete unit offset so that the angle of the complete unit indicated by letter *a* corresponds with the angle *b* of one of the repeats in an adjacent vertical row.

I claim:

The ornamental design for a textile fabric or similar article, as shown and described.

ARNOLD ZAVELL.
